(57) **CLAIM**

The ornamental design for a food container, as shown and described.

DESCRIPTION

The present application refers to a new and original food container that consists of a house-hold instrument used to packaging food products.

The food container has a new, exclusive and modern design which provides the product an esthetic appeal.

FIG. 1 shows an upper perspective view of the food container, FIG. 2 shows a bottom perspective view of the food container, FIG. 3 shows an upper view of the food container, FIG. 4 shows a bottom view of the food container, FIG. 5 shows the front side of the food container; and, FIG. 6 shows any side view of the food container.
